DESIGN FOR A SHOE

Thomas F. Barlow, Waterville, Maine

Application November 15, 1944, Serial No. 116,341

Term of patent 3½ years

(CL. D7—7)

To all whom it may concern:

Be it known that I, Thomas F. Barlow, a citizen of the United States of America, residing at Waterville, county of Kennebec and State of Maine, have invented a new, original, and ornamental Design for a Shoe, of which the following is a specification, reference being had to the accompanying drawing, forming a part thereof.

The design for a shoe is characterized by the zippered purse of the configuration and positioned on the instep of the shoe in a manner illustrated on the drawing.

I claim:

The ornamental design for a shoe, as shown and described.

THOMAS F. BARLOW.
